(54) **WASHING MACHINE**

(76) Inventor: **James H. Little**

James H. Littel
Letters Patent (Patented July 2, 1856)

The object is referred to in these letters Patent and making part of the same containing a description in the words of the same James H. Littel himself of his improvements in the Washing machine.

Description of the Washing Machine. — First a strong box is to be made of well seasoned pine stuff about one inch in thickness. The Box should be about 28 inches in width in the inside, and four feet long, at — At the extremity of the box, at which the crank is placed, it should be about 6. inches in depth so as to give space for the motion of a crank of about 5 inches. The sides of the machine at the other extremity, — should be about two feet wide for the space of 16 inches from the end, so as to cover and enclose the upright pitman and the rod upon which they are suspended. The bottom of the box at this extremity, should be made so as to form a curve or in case of a circle for the space of about 28 inches to correspond with the one performed by the beaters, or paddles of the machine when in operation. Two thirds of the distance from the circular extremity of the machine the box should be closely covered to prevent the escape of the suds, when the machine is in operation. The end of the machine should have a curve of less circumference than the bottom to give the paddles proper space and to give them a turning and upward motion during the operation of the machine, at the plumb of the machine, at a proper distance from the shallow end of the box metallic Boxes should be placed on, and secured to its edges by screws or otherwise, for the bearing of the crank which is to give motion to the machine. On these boxes, is placed a triple crank of metal or wood (the for-

one of which is preferred,) divided into equal triple divisions, of a circle, for the attachment of the extremities of those inclined pitmans. At one extremity it should have an arm about 14 inches in length with a suitable handle for the application of manual power, but it is intended for the application of all kinds of power and should be varied in its construction, accordingly. To each of the bearings of this crank is attached the end of an inclined Pitman about 2 feet and eight inches long, connected at their other extremities to the beaters or pounders by mortise and pin or such other hinge connection as the builder shall prefer. A cast or wrought iron crank of about one inch in diameter etc., would be a suitable size for a machine of these dimensions, to be used by manual power and can be varied according to the size of the machine, and the degree and kind of power to be applied thereto. Three pounders or beaters are connected as follows, viz. Depth about 12 inches, thickness $6\frac{1}{2}$ inches, length at top about 5 inches, at bottom about 10 inches and to correspond in curvature with the bottom of the machine beneath them. The faces of the pounders to have a concave surface of about the same arch (but reversed) as the end of the machine opposite to them and between which the articles to be cleaned are to be placed. The faces of the beaters to be filed horizontally to the depth of one or two inches, and may be also filed perpendicular to about the same depth; in which case the extremities of the projections should have a surface of about one inch square. These faces may be of iron, or other metal if desired by the builder. The beaters are suspended from a rod across the top of the machine, by a right pitman, of a length required by the arc of the circle of the bottom of the machine beneath them. There can be more or less than

three beaters connected with the crank by it being divided into a greater or less number of equal divisions of an arch but the number three is recommended as convenient and suitable for the purposes of the machine. The machine should be placed on a suitable frame, at the height of about 14 inches from the floor to allow a convenient space for placing a tub or rail beneath it to receive the laundry and to be convenient for the operation of working and using the machine. The machine may also be put in operation by eccentric circles upon the shaft instead of cranks, if a preference should be given to that mode of operation, but which would be more expensive in its construction.

I claim the application of the triple crank, the inclined pitman, and the triple beaters as applied to washing machines and the principles of the applications thereof whether of a greater or less number, and whether the power and motion is communicated by cranks or eccentric circles. The advantages of this machine are believed to consist in a more equal division of power by the triple crank, and in the constant and rapid succession of the beats upon the clothes in the reacting power of the water in forcing back the beaters in succession to each other, and in the simple and convenient manner of its application to the purposes intended.

The manner of its use for the purpose of washing clothes does not differ from other machines so much as to require any definite instructions.
